UNITED STATES PATENT OFFICE.

ELISHA N. FALES, OF DAYTON, OHIO.

HELICOPTER FLYING MACHINE.

Application filed May 11, 1921. Serial No. 468,740.

To all whom it may concern:

Be it known that I, ELISHA N. FALES, a citizen of the United States, residing at 760 Ferguson Ave., Dayton, in the county of 5 Montgomery and State of Ohio, have invented certain new and useful Improvements in Helicopter Flying Machines, of which the following is a specification.

This invention relates to helicopter flying machines, the object in view being to provide a machine employing oppositely extending wings or supporting surfaces, having their leading edges disposed reversely to each other; the wing structure having 10 suspended centrally beneath the same—a car having directional and stabilizing means.

The invention relates particularly to the means for driving the wings around a central axis from which the car is pivotally 20 suspended. It also contemplates a releasable connection between the car and the wing structure, together with a parachute arrangement whereby, in case of necessity, the car may be released from the wing structure and one or more parachutes, normally housed within the car, released so that a safe 25 descent to the ground may be effected.

A further object of the invention is to provide in connection with the car, a landing chassis embodying hinged supporting legs which are capable of adjustment and which carry the controlling directional and stabilizing members, all of which are under 30 the control of the operator seated in the car.

With the above and other objects in view, the invention consists in the novel construction, combination and arrangement herein 35 fully described, illustrated and claimed.

In the accompanying drawings:

40 Fig. 1 is a plan view of a helicopter flying machine, embodying the invention;

Fig. 2 is a view partly in plan and partly in section, showing modified wing propelling means;

45 Fig. 3 is a side elevation, partly in section, of the machine on an enlarged scale;

Fig. 4 is a fragmentary, vertical section on an enlarged scale, showing the releasable connection between the car and wing structure;

50 Fig. 5 is a diagrammatical side elevation illustrating the parachute arrangement for

supporting the car after the latter is released from the superstructure.

Fig. 6 is a similar view, showing the use 55 of a plurality of parachutes;

Fig. 7 is a side elevation of the car, showing the supporting chassis;

Fig. 8 is an end view of the car, showing another arrangement of supporting chassis; 60

Figures 9 and 10 are reduced diagrammatic views in plan and side elevation showing means to direct the car.

The improved helicopter flying machine embodies in the drawings, a pair of oppositely extending wings or supporting surfaces 10, having their leading edges 11 facing in opposite directions. The wings 10 are rigidly connected at the center of the machine and are preferably arranged at any 70 suitable dihedral angle to each other.

Supported separately of the wing structure, I have shown a fuel tank 12, an air compressor 13, and a combustion chamber 14. Pipes or conduits 15 lead from the air 75 compressor or combustion chamber toward the wing tips and, under the arrangement shown in Fig. 1 of the drawings, said pipes lead to the hubs of propellers 16 which are shown as mounted behind the trailing edges 80 17 of the wings 10. The expanding gases pass from the hub of the propeller outwardly thru the passages 18 to the propeller tips and thence escape through jet nozzles 19 which discharge in a direction 85 contrary to the normal direction of rotation of the propeller blades, the propellers being thus driven by reaction.

By means of the arrangement above described, the wings are driven in a circular 90 path around the central axis of the machine where there is a normally vertical shaft 20 extending downwardly from the wing structure and having a car or fuselage 21 suspended thereon. Instead of the propelling 95 means above described, the gas under pressure may be delivered from the compressor 13 through passages 22 extending longitudinally of the propeller blades into jet nozzles 23, extending rearwardly from the propeller 100 blades and ignited by spark plugs 24 in the nozzles, as shown in Figure 2.

For driving the machine in an approximately horizontal path, the car 21 may carry

an engine which drives a propeller 25 at one end of the car. The shaft 20 has at the lower end thereof, a spider 26 having downwardly extending fingers 27 formed with 5 latch receiving openings 28. The fingers 27 extend downwardly through openings 29 in the main frame members 30 of the car 21, as best illustrated in Fig. 4. The openings 28 are adapted to receive a corresponding 10 number of sliding latches 31 all connected by flexible means 32 to a centrally arranged drum 33 on a shaft 34 journaled in a bearing bracket 35 within the car 21. The shaft 34 may be turned by means of a crank 36, 15 the shaft of which has a worm 37, meshing with a worm-gear 38 on the shaft 34. By the means just described, the operator in the car may simultaneously draw inwardly all the latches 31 and thereby release car 21 20 from the wing structure above.

In order to enable the car 21 to descend slowly and make a safe landing, one or more parachutes are arranged in a parachute compartment 39 within the car. In Figures 25 5 and 6 I have illustrated the use of a plurality of parachutes, one of which is connected by an anchor rope 40 to said car, and another of which is connected by an anchor rope 41 to the car. As shown, the 30 anchor rope 40 passes upwardly thru the vent-hole 42 of the other parachute 43. As illustrated in Fig. 6, this one parachute is adapted to be released before the other or others, the succeeding parachute pack 44 being mounted upon the primary parachute anchor rope 40. Connected to the pack 44 is a pilot parachute 45 which the aviator throws from the compartment 39; and when 35 said pilot parachute 45 opens, it effects an opening of the parachute in pack 44, the last named parachute then assuming the position and relation to the parachute just released, as shown in Fig. 5. As many 40 parachutes may be used as are found necessary to support the car and enable a safe 45 landing to be effected.

The chassis, which supports the car 20, comprises a plurality of supporting legs which are pivotally connected to the car at 50 47 and carry wheels 48 at their downward ends. The legs 46 are adapted to be moved laterally and upwardly from the supporting 55 position shown in Figs. 7 and 8 to a horizontal stabilizing or controlling position. A normally horizontal vane or elevator 49 is pivotally mounted under the fuselage at 50 and provided with horns 51 to which are attached flexible controls 52 leading into the car.

60 The legs referred to also have mounted thereon a normally horizontal vane 53, connected in like manner by controls 54 with a lever or the like in the car 20. Stops 55 are used to hold the legs 46 in a horizontal position, in which position the stabilizing

vanes 53 are used for maintaining lateral balance of the machine. The vane 53 operates in a manner similar to the ailerons of an airplane. The vane 49 operates similarly to the usual elevator, and the vanes 53 are intended to be used for directional purposes similar to the vertical rudder of an airplane.

The machine, as a whole, operates on the principle of two airplanes flying around 75 a common center. The body is suspended below the rotating wing structure above, rotation of the wings being caused by the reaction propelling means above referred to. The wings may be of monoplane or 80 biplane construction and any desired number of propelling elements may be employed in connection therewith. The propelling elements operate in opposite directions and form a driving couple whose reaction is 85 against the atmospheric air itself. The body or car is prevented from rotating by means of the vanes herein shown and described which oppose rotation by their own resistance. Horizontal translation 90 may be produced by the propelling means on the body or car.

The car will provide space for operator, passengers, equipment, machinery, etc.

By shifting the center of gravity of the 95 car, the direction of movement of the flying machine may be controlled.

For maneuvering on the ground, the landing wheels may be provided with shock-absorbers of any kind. 100

I claim:

1. In a helicopter flying machine, wings extending in opposite direction from the center of the machine and having their leading edges disposed reversely to each other, propelling means for said wings, a car suspended from the center of the machine and having a swiveled connection with the superposed wing structure, means for disconnecting the car from the wing structure while in flight, and a releasable parachute attached to and normally housed within the car. 105

2. In a helicopter flying machine, wings extending in opposite direction from the center of the machine and having their leading edges disposed reversely to each other, propelling means for said wings, a car suspended from the center of the machine and having a swiveled connection 110 with the superposed wing structure, means for disconnecting the car from the wing structure while in flight, and a releasable parachute attached to and normally housed within the car, said disconnecting means 115 embodying a plurality of latches, and means for simultaneously operating said latches. 120

3. In a helicopter flying machine, wings extending in opposite direction from the 125

center of the machine and having their parachutes normally housed within the car leading edges disposed reversely to each and strung upon a common guide rope 10 other, propelling means for said wings, a which forms the anchor rope of one of the car suspended from the center of the ma- parachutes.
5 chine and having a swiveled connection In testimony whereof I have affixed my with the superposed wing structure, means signature.
for disconnecting the car from the wing structure while in flight, and a plurality of

ELISHA N. FALES.
